UNITED STATES PATENT OFFICE.

DANIEL POLLACK, OF NEW YORK, N. Y., ASSIGNOR TO MAJESTIC METAL SPECIALTIES, INC., OF NEW YORK, N. Y., A CORPORATION OF NEW YORK.

DESIGN FOR A VANITY CASE OR SIMILAR ARTICLE.

Application filed August 2, 1927. Serial No. 22,977. Term of patent 3½ years.

To all whom it may concern:

Be it known that I, DANIEL POLLACK, a citizen of the United States, residing at New York city, county of New York, borough of Manhattan, and State of New York, have invented a new, original, and ornamental Design for a Vanity Case or Similar Article, of which the following is a specification, reference being had to the accompanying drawing, forming part thereof.

I claim:

The ornamental design for a vanity case or similar article, as shown.

DANIEL POLLACK.
